CARPET SWEEPER

Paul Heftler, Chicago, Ill.

Application November 26, 1941, Serial No. 420,443

18 Claims. (Cl. 15—41)

1

The inventions described in this specification and shown in the accompanying drawings are improvements in carpet sweepers and particularly in "high-low mechanisms" for carpet sweepers. A "high-low mechanism," as the term is used by those in the carpet sweeper business, is a mechanism that lowers the brush of the carpet sweeper with respect to the case as the wheels rise with respect to the case, so that, when the sweeper is resting on the floor and the case is pushed down by pressing down on the handle of the sweeper, the brush will move down faster than the case and come into contact with the surface to be swept sooner than if the brush were carried directly by the case.

The principal objects of these inventions are to provide high-low mechanisms that operate with less friction than those now in use and to provide high-low mechanisms that are cheaper to make than those now known so that this type of mechanism can be put on even the lowest priced sweepers instead of being restricted, as they are now, to sweepers selling for \$5.00 or more.

Other objects will be apparent from the following description and the accompanying drawings, in which:

Figure 1 is an end view, with a part of the end cover 8 broken away, of one design of carpet sweeper embodying some of the inventions;

Figure 2 is a bottom view, on a larger scale, of the mechanism shown in Figure 1;

Figure 3 is a section on the line 3—3 in Figure 1;

Figure 4 is a section on the line 4—4 in Figure 2;

Figure 5 is a section on the line 5—5 in Figure 4;

Figure 6 is a section on the line 6—6 in Figure 2;

Figure 7 is an end view, with a part of the end cover 68 broken away, of another design of carpet sweeper embodying some of the inventions;

Figure 8 is a section approximately on the line 8—8 in Figure 7, on a larger scale;

Figure 9 is a section on the line 9—9 in Figure 8;

Figure 10 is an end view of a part of a sweeper similar to the one shown in Figure 7 but modified in some details;

Figure 11 is a plan view and partial section of the parts shown in Figure 10;

Figure 12 is an end view, with a part of the end cover 102 broken away, of another design of carpet sweeper embodying some of the inventions;

Figure 13 is a section on the line 13—13 in Figure 12, on a larger scale;

Figure 14 is a section on the line 14—14 in Figure 12, on the same scale as Figure 13;

2

Figure 15 is an end view of a part of a sweeper similar to the one shown in Figure 12 but modified in some details; and

Figure 16 is a section on the line 16—16 in Figure 15, on a slightly larger scale.

The sweeper shown in Figures 1 to 6

In this sweeper, the wheels, brush, dust pans, handle, and main portion of the case are conventional. The novel parts of the sweeper are the high-low mechanism, the end covers of the case that carry the high-low mechanism, and the connections between the high-low mechanism and the brush and the wheels. However, all of the sweeper is illustrated in the drawings and is described below in detail in order that it will be quite clear how the novel parts of the sweeper are combined with the conventional parts to form a highly integrated structure that is economical to manufacture and which works well.

The case and handle (Figures 1 to 3)

The main part of the case 1 is formed by a pair of metal end plates 2 and a sheet metal member 3 connecting the end plates together and forming the top and sides of the case. The top and side member 3 is formed with flanges 4 at each end of the portion forming the top, and these flanges overlap the upper edges of the end plates 2 and are spot welded to them. The ends of the end plates 2 are bent out to form vertical flanges 5 almost but not quite in line with the portions of the top and side member that form the sides of the case, and the side portions 6 are provided with extensions 7 that overlie the flanges 5 and that are also slightly out of line with the side portions 6.

The flanges 5 and the side extensions 7 are slightly out of line with the side portions 6 so that the flanged edges of the end covers 8 can fit over them and still lie flush with the main portions of the sides 6. Rivets 9 fix the end covers 8 to the flanges 5 on the end plates and to the side extensions 7, and they also serve to fix the flanges 5 and the side extensions 7 to each other.

The end covers 8 are generally dome shaped and fit against the ends of the case 1 so as to form a smooth "streamline" assembly, but each cover has a horizontally extending step or re-entrant angle 10 formed in it near the top. Above the angle 10, the end cover has a short vertical portion 11 out of which are punched two ears or lugs 12, the lugs 12 extending towards each other on the inside of the vertical wall 11 of the end cover and cooperating with it to form a guide or slideway in which a portion of the high-low mechanism described below can slide up and down. Below the angle 10, the end cover bellies out to provide room for the operation of

other parts of the high-low mechanism, and it has two inwardly projecting bosses 13 on which the high-low mechanism is supported.

The case is encircled by a conventional rubber bumper 14, which covers and conceals the depressions or hollows formed on the outside of the end cover 8 by the bosses 13 and which is held in place by clips 15 punched out of the end cover. The sweeper is operated by a conventional handle having a bail 17 which straddles the main part 10 of the case 1 and whose ends 18 are bent in to form trunnions fitting into bearings 19 in the end plates. Each end plate is formed with two bosses 20 above the handle bearing 19, the bosses being spaced apart and located so as to receive the leg of the bail 17 between them when the handle is vertical and to hold the bail and handle in that position. When the sweeper is to be used, the handle is swung to one side or the other, and the legs of the bail spring over the bosses 20 and permit the handle to swing freely.

The case is provided with conventional dust pans 21, one at either side of the brush, and with conventional means for dumping them, but these are not illustrated or described in detail because their relation to the rest of the sweeper is the same as in the ordinary sweeper.

The wheels and axles (Figures 1, 2 and 4)

Each of the four wheels of the sweeper is made of two sheet metal discs 24 and 25 which lie in contact with each other over most of their area and which are secured together by four tubular rivets 26. The rivets 26 are formed integrally with the outer disc 24 and extend through holes and are clenched over the inner disc 25. The rims of the discs 24 and 25 are formed into cylindrical flanges 27 and 28 with radially extending lips or small flanges 29 and 30 at their outer edges, and a rubber tire 31 is seated on the flanges 27 and 28 between the lips 29 and 30.

The centers of the two wheel discs 24 and 25 are shaped to fit around a ring of steel balls 32, and they thus form the outer race of a ball bearing. The inner race of the bearing is formed by a groove in a hub 33 which is mounted on an axle 34 extending through the case, the end plates 2 being formed with holes 35 through which the axles pass. Where the axles pass through the end plates, they are provided with bushings 36 made of wood, plastic or other non-metallic material to prevent the sound made by the axles striking the end plates from being too "tinny." The holes 35 through which the axles and bushings pass are large enough to allow them to move up and down three eighths of an inch or more and to move a similar distance across. The bushings 36 are formed with flanges that extend out over the holes 35, covering the holes and also preventing the bushings from sliding in on the axles.

The bushings 36 and wheel hubs 33 are sliding fits on the axles so that they can be easily assembled. They are held on by links 55 which interlock with the ends of the axles 34. Near each end of each axle, there are two notches 37 on opposite sides so that the cross-section of the axle at that point is as shown at 34 in Fig. 4. Each link 55 is formed of a flat piece of sheet metal with a long keyhole slot or hole 56 punched in it. The lower end of the hole 56 is large enough so that the round end of the axle can be slid through it to bring the notches 37 in line with the link, and the upper part of the hole is just wide enough to take the notched part of the

axle. Thus the link cannot slide off of the end of the axle, and it holds the wheel on and also prevents the axle from turning and winding up on itself the threads that may be swept up by the brush and thrown up onto the axle. The lower ends of the links 55 are pivoted to the high-low brush adjusting mechanism, as described in detail below.

The brush (Figures 1 to 3)

The brush assembly is built up on a wooden core 38 into which the tufts of bristles 39 are set in the usual manner in five or six wavy rows extending along the brush. Each end of the brush core 38 is necked down and extends out through a large notch in the end plate 2 of the case, and it carries a metal pulley or friction wheel 40 which lies between and is driven by the wheels and tires 31. Each end of the brush core 38 also has a central hole 41 drilled into it to receive the bearing 64 which carries the brush and which forms a part of the high-low mechanism.

The high-low mechanism (Figures 1 to 6)

The high-low mechanism is what adjusts the brush up and down with respect to the case as the case moves up and down with respect to the wheels, and it enables the sweeper to adjust itself to rugs and carpets of different thicknesses and softnesses and to bare floors. This mechanism includes a pair of dog-legged levers 42 and 43, which are fulcrumed or pivoted on shoulder rivets 44 fixed to the bosses 13 on the inside of the end cover. One of the two levers, 30 the right-hand one 43, is shown on an enlarged scale in Figures 4 and 5 as well as in Figure 2, and it has one arm 45 that extends horizontally towards the axis of the brush and another arm 46 that extends down at an angle in the opposite direction. The sloping arm 46 has an end portion 47 bent in at right angles to its main portion, and the end portion 47, in turn, carries a tail 48 that extends straight down from its inner edge. The end portion 47 of the lever has a hole 45 49 through which one end of a rod spring is hooked, and an offset lug 50 projects in back of the spring near the fulcrum of the lever to keep the spring in a plane parallel to the general plane of the lever.

50 The horizontal arm 45 of the lever is offset to the outside, as shown in Figure 2, so that its end lies in the space provided by the bellying out of the end cover below the horizontal step 10. The end of the arm 45 is formed with a round hole in which is journaled a shoulder rivet 52 fixed to the brush pivot carrier described below. The other lever 42 is exactly symmetrical with the lever 43 which has just been described, one being a mirror image of the other, excepting that the 55 hole 53 in the horizontal arm of the left-handed lever 42 is a horizontally extending slot, as shown in Figure 6, instead of being a round hole. This permits the shoulder rivet 54 which is journaled in it to not only turn with respect to the arm 45 but also to slide back and forth a little. The bent-in part 47 at the end of the sloping arm of each lever fits in the ground end of the slot 56 in one of the links 55, and the depending tail 48 on the end of the lever prevents the link from 60 sliding off.

The spring 57 which hooks into the holes 49 in the end portions of the levers is one of the two main springs of the sweeper, there being one such spring at each end of the sweeper for each pair of wheels. The spring is made up of a horizontal

central portion and two depending leg portions joined to the central portion by coils 58 and terminating in hooks 59, and it is supported entirely by the levers. Before it is assembled into the sweeper, its leg portions extend towards each other, approximately parallel to its central portion, and overlap, so that, when it is in the sweeper, it tends to swing the sloping outer arms 46 of the levers towards each other. This causes the levers to pull down on the links and thus tends to force the wheels and axles down with respect to the case, transferring the weight of the case to the wheels.

The inner ends of the levers 42 and 43 are connected to each other and to the brush through a brush pivot carrier 60, which is formed of a single E-shaped piece of spring metal, the back of the E extending horizontally and the three legs 61, 62 and 63 depending from it. The "back" or top of the carrier 60 lies on the inside of the vertical part 11 of the end cover above the step 10, and it is held by the lugs 12 so that it can slide vertically. One outer leg 63 of the carrier has fixed to it the shoulder rivet 52 which is journaled in the round hole in the inner end of the right lever 43, and the lower part of the carrier is thus guided in a fixed path. The other outer leg 61 of the carrier has fixed to it the shoulder rivet 54 which is journaled in the elongated hole 53 in the inner end of the left lever 42, and the slight horizontal movement permitted by the elongated hole 53 prevents there being any "fighting" between the parts as they move up and down. The central leg 62 of the carrier has the brush pivot 64 riveted to it, the pivot fitting in the bearing 41 in the end of the brush and holding the brush in place.

The bellying out of the end plates 2 described above and the springiness of the brush pivot carriers permits the brush to be removed easily when it is necessary to comb threads and lint out of it. To remove the brush, the lower end of the central leg 62 of the carrier is pressed out with the thumb or finger of one hand, thus partly withdrawing the brush pivot from the brush. The pivot is not entirely withdrawn by this operation because the end cover is not bellied out quite far enough to permit this, as it is not necessary. Complete withdrawal of the brush pivot is secured by placing two fingers of the other hand on the outside of the brush pulley, one finger at either side of the brush pivot arm 62, and pushing the entire brush towards the other end of the sweeper. This movement, which is permitted by the springiness of the brush pivot carrier at the other end of the sweeper and by the fact that the outer legs 61 and 62 of the carrier and the arms of the levers to which they are connected are offset away from the brush, completely frees the brush from its pivot and allows one end of it to be swung out of the sweeper. The other end of the brush is then freed in a similar way, and this completes the removal of the brush from the sweeper.

In manufacturing and assembling the sweeper, a certain procedure will be found to be most efficient. Certain sub-assemblies are first prepared, these sub-assemblies being (1) the case complete with dust pans and their dumping mechanism but without the end covers 8 or the bumper 14, (2) four wheels assembled with their tires and hubs, (3) two end covers 8, each with the two levers 42 and 43, the spring 57, and the brush pivot carrier 60 and pivot 64 assembled on it, and (4) the brush. In preparing the end cover 75

sub-assemblies, it is best to perform the following operations in the order given: (1) rivet the brush pivot 64 to its carrier, (2) secure the carrier to one lever 43 by the pivot 52, (3) hook one end of the spring to that lever and to the other lever 42, (4) place the lugs 50 on the levers behind the legs of the spring, (5) secure the carrier to the other lever 42 by their pivot 53, (6) slide the upper end of the carrier 60 between and under the lugs 12 on the inside of the end cover, and (7) secure the levers to the end cover by their fulcrums 44.

In the final assembly of the sweeper, a link 55 is placed on one end of each of the two axles, and the links are then hooked onto the end portions of the levers on one end cover assembly. A wheel assembly and a bushing 36 is then slid on each axle, and the case is then slid onto the axles into position on the end cover. Two more bushings 36 and the other two wheels are then slid onto the other ends of the axles, and two more links 55 are hooked into the notches on those ends of the axles. The foregoing is done with the sweeper standing on end, and it remains in that position during the next step in the assembly. The next step consists in taking a second end cover assembly, placing it upright above the end of the sweeper and inserting the tails 48 of the levers in the round ends of the holes in the links 55, and swinging the end cover down onto the end of the sweeper. The rivets 9 which hold the end covers to the case are then put in, and the bumper 14 is put on. The handle bail 17 can be sprung into place before the end covers are put on, or the end covers can be made with enough clearance at the top between their edges and the case to permit the bail to be sprung into place after the end covers are put on. This completes the assembly.

The sweeper shown in Figures 7 to 9

Many of the parts of this sweeper, such as the case 1, the bumper 14, the handle bail 17, the wheel discs 24 and 25, the tires 31, the ball bearings 32, the axle bushings 36, the brush 38-39, and the brush pulleys 40 are identical with the corresponding parts of the sweeper shown in Figures 1 to 6 and are identified with the same numbers. The differences between the two sweepers are in the high-low mechanisms and in some of the parts to which the high-low mechanisms are connected.

In the sweeper shown in Figures 7 to 9, the end cover 68 is formed with a pair of bosses 69 on the inside, on either side of the axis of the brush 38-39, and the bosses 69 have riveted to them the fulcrums 70 and 71 of the high-low mechanism described below.

The hubs 72 of the wheels are drilled lengthwise to receive the ends of the axles 73, but the holes for the axles do not extend all of the way to the outer ends of the hubs; this keeps the axles 73 from sliding out against the end cover 68. The outer ends of the hubs 72 project out beyond the sides of the wheels, and each one is formed with a large groove 74 that extends around it. The bottom of each groove 74 is serrated across, so that this section of the hub 72 is like a gear with fine teeth, as shown in Figure 9. The serrations at the bottom of the groove 74 can be made on a screw machine at the same time that the rest of the hub is machined by using a tool similar to a knurling tool.

The high-low mechanism (Figures 8 and 9)

The high-low mechanism consists of merely two

levers 76 and 77, their two fulcrums 70 and 71, and a spring 78, and it is so simple that it adds only a few cents to the cost of the sweeper, thus making it practical for even the cheapest sweepers to be provided with a high-low brush adjusting mechanism.

The primary lever 76, which is the one to which the brush pivot 79 is riveted, is formed of a single piece of springy sheet metal. It has a body part 80 at the end away from the brush pivot 79, and three arms 81, 82 and 83 extend from the body towards the brush pivot. The central arm 82 extends to just beyond the fulcrum 70 and is pivoted on it, and the other two arms 81 and 83 curve together beyond the end of the central arm and have the brush pivot 79 riveted to them. The two outer arms 81 and 83, in reality, are a single arm divided into two over a part of its length to enable the entire lever 76 to be easily stamped out of one piece of sheet metal without any difficult forming operations.

The outer end or body part 80 of the lever is formed with a diagonal slot 84 that slopes down and away from the brush pivot 79 and that has small teeth 85 along its upper edge. The slot is wide enough so that the grooved part of the wheel hub 72 can slide freely in it past the teeth 85, and the teeth are of the right size and spacing to gear with the serrations 75 at the bottom of the groove 74 in the hub when the hub is pressed against the upper serrated side of the slot.

The end of the central arm 82, beyond the fulcrum 70, is formed into a small tube 86 which tightly grips one end of the spring 78, which is a piece of spring wire formed into two flat curly cues curling around the two lever pivots or fulcrums 70 and 71. The part of the spring that fits in the tube 86 on the lever is straight, so that the tube 86 can be straight and easy to make, but there is a sharp bend in the spring at each end of the tube to positively prevent the spring from sliding.

The other end of the spring is connected to the other lever 77 in the same way as the first end is connected to the first lever 76. The other, or secondary lever, 77 is the same as the first lever 76 except for certain minor differences. Instead of having the brush pivot 79 riveted to it, the secondary lever has a slot 87 through which a neck on the brush pivot extends and in which it can slide back and forth a little as the levers swing up and down. The end of the lever 77 lies in the same plane as the rest of the lever, while the end of the primary lever 76 is offset a little from the plane of the rest of the lever 76 so that the main portions of the two levers can lie in the same plane while their ends overlap. Finally, the secondary lever 77 has an ear 88 that projects down from the part that engages the brush pivot 79 and which makes it easier to spring the levers out when the brush is to be removed.

The brush 38-39 is removed by pinching the ear 88 on the secondary lever 77 against the inside of the end cover 68 with one hand, which bends the levers 76 and 77 out and withdraws the brush pivot 79 halfway from its bearing 41 in the brush core, and at the same time pushing the brush towards the other end of the sweeper, which withdraws the brush pivot the rest of the way from its bearing. That end of the brush is then swung out, and the other end is freed in the same way.

When the sweeper is in operation, the wheel hubs 72 will tend to roll up to the upper ends of the oblique slots 84 in the levers, and this will

force the wheels against the brush pulley 40 and provide the necessary traction between them. At the same time, the "gear action" between the teeth 85 on the edge of the slots and the serrations 75 in the bottoms of the grooves in the wheel hubs will positively prevent the wheel hubs or the axles from spinning with the wheels.

The way in which the sweeper is assembled during manufacture is obvious, except that the wheels are placed in the end covers, with their hubs engaged in the slots in the levers, and the assembly thus formed is then assembled to the case and axles.

A modified high-low mechanism (Figures 10 and 11)

The high-low mechanism can be modified slightly, and perhaps made even cheaper to construct, by making the changes shown in Figures 10 and 11. The hub 33 of the wheel is made shorter, and the axle 91 extends clear through it and has its end 92 flattened to hold the hub 33 from sliding off. The oblique slot 93 in the lever 94 is made narrow enough to prevent the flat end 92 of the axle, which fits in it, from turning but wide enough so that it can slide easily along it. In assembling this form of the mechanism, the wheels are placed on the axles and the ends of the axles are flattened, and then the end covers carrying the high-low mechanism are put in place.

The sweeper shown in Figures 12 to 14

This sweeper differs from those shown in Figures 1 to 11 in that its case 101 is of wood, its axles 119 rotate with the wheels 114, the wheels are of different construction, and the high-low mechanism is different.

The case (Figures 12 and 13)

The main part of the case 101 is formed of a pair of end pieces 102, a pair of side rails or pieces 103 into which the end pieces 102 are rabbed, and a single piece of thin curved plywood 104 forming the top and extending down over the outside of the side pieces 103. As may be seen in Figure 12, each side rail 103 is formed with a shallow rabbet 105 extending lengthwise along its upper edge, leaving a flat surface below it to which the flat end of the piece of plywood is glued.

The case is completed by "streamline" metal end covers 109, which fit against the ends of the wooden case 101 and whose outer surfaces lie flush with and form smooth continuations of the outer surface of the plywood 104. The tops of the end covers 109 are formed with wide shallow notches which form slots at each end of the case 101 through which the handle bail 107 extends. Each end cover 109 is held in place by two screws 110 extending into the end 102 of the wooden case, and spacing tubes or sleeves 111 are provided around the screws 110 between the case end 102 and the parts of the end cover 109 through which the screws pass so that the screws may be turned up tight without bending the end cover.

The heads of the screws 110 lie in shallow recesses in the end cover, and they are covered by the conventional rubber bumper 112 which encircles the sweeper. The bumper 112 may be supported by clips formed out of the end cover, as in the sweepers shown in Figures 1 to 11, or it may be nailed to the wooden case 101. The bumper 112 also conceals, although it does not cover, an opening 145 in the center of the end

cover 109 just above its lower edge. The lower edge of the opening 145 is strengthened by an inwardly extending flange, and it serves as a fulcrum for a screw-driver or other lever used in removing the brush as described below.

The wheels and axles (Figure 14)

Each wheel is formed of a single disc of sheet metal 114 having a flange 115 which forms its rim and on which a rubber tire 116 is cemented. The center of the disc 114 is stiffened by a washer 118 and is riveted to a hub 117, which is a sliding fit on the axle 119. The axle 119 extends through the case 101, and the part within the case is enclosed by an axle tube 108 so that threads picked up by the sweeper will not become wound up on the axle, which turns with the wheels.

The axle tubes 108 are fixed in the ends 102 of the case, and they are large enough to permit the wheels 114 and axles 119 to move up and down freely with respect to the case 101 as the sweeper adjusts itself to the surface being swept. The ends of the axle tubes 108 are covered by washers 121 carried by the axles between the wheels and the ends 102 of the case, and the washers 121 keep the inner ends of the wheel hubs from hooking into the axle tubes and keep the wheels from moving in towards the case. Accidental outward movement of the wheels is prevented by anti-friction wheels or rollers 135, forming parts of the high-low mechanism and engaging the axles 119 just outside of the wheel hubs 117, and accidental outward movement of the axles 119 is prevented by spring brackets 130, which carry the high-low mechanism and lie just at the ends of the axles.

The brush (Figures 12 and 13)

The brush assembly is similar to that in any conventional sweeper and consists of a brush core 122, bristles 123 set into the brush core, and a pulley 124 on each end of the brush core. The core 122 is preferably of wood, for cheapness, and has a hole 125 in each end which forms a bearing for the brush pivot 133. The pulley 124 may be of metal, like the pulley shown in Figure 3, or of wood or plywood, or of wood covered with a metal rim.

The high-low mechanism (Figures 12 to 14)

The high-low mechanism is formed of two levers 126 and 127 which are pivoted on shoulder rivets 128 and 129 carried by a spring bracket 130. One lever 126, called the primary lever, has the brush pivot 133 riveted to an arm 132 which extends approximately horizontally from the pivot or fulcrum 128. Another arm 134 of the primary lever curves around over the axle 119 and carries an anti-friction wheel 135 on a shoulder rivet 136 which forms its bearing, the anti-friction wheel being located so that it rides on the upper and outer side of the axle right next to the end of the wheel hub 117. The anti-friction wheel 135 presses on the axle 119 at an angle of about 45° to the vertical, and it thus holds the wheel 115 and axle 119 pressed towards the brush pulley 124 as well as towards the floor.

The diameter of the anti-friction wheel 135 is several times as great as the diameter of the axle 119 upon which it rolls. Hence, the anti-friction wheel 135 will turn at a speed which is only a small fraction of the speed of the floor wheel 115, and the friction will be only a small fraction of what it would be if the floor wheel turned on its axle.

The primary lever 126 also includes an arm 137 which extends down below the level of the fulcrum 128 almost to the lower edge of the end

cover 109 of the case and which terminates in a short outwardly bent end 138 with a hole in it. The secondary lever 127 is similar in every way to the primary lever 126, except that its horizontal arm 140 is offset a little to one side so that it will lie alongside of the horizontal arm 126 of the primary lever, and it has a slot through which the brush pivot 133 passes instead of having the brush pivot riveted to it.

10 A spring 142 is hooked into the holes in the lugs 138 and 139 on the two levers, pulling the lugs towards each other and causing the levers and their anti-friction wheels to press down on the axles of the floor wheels 115. The spring 142 may be identical with the spring 57 of the sweeper shown in Figs. 1 to 6, but it is preferably a simple coil spring stretched between the lugs 138 and 139 and having coils near each end and a straight wire part 143 in the center so that it will be less in the way when the brush is being removed.

20 The spring bracket 130 is formed of a strip of springy steel, and it is held in place by having its ends clamped under the ends of the spacing sleeves 111 on the end cover screws 110. At the center of the sweeper, the spring bracket 130 passes just above the level of the hole 145 near the bottom of the end cover 109 and is spaced in a short distance from the end cover. The arrangement is such that a screwdriver can easily be inserted into the hole 145 and under the center of the lower edge of the spring bracket 130, and the spring bracket can be pried out far enough to more than half withdraw the brush pivot 133 from its bearing 125 in the end of the brush 122. At the same time, the brush can be pushed towards the other end of the sweeper by pressing on the side of the brush pulley 124, this movement of the brush being permitted by the flexing of the spring bracket at the other end of the sweeper, and thus freed entirely from its pivot 133. The other end of the brush can then be freed in a similar way, and the entire brush removed from the sweeper.

45 *A modified high-low mechanism (Figures 15 and 16)*

The high-low mechanism can be modified, as shown in Figures 15 and 16, so as to require slightly less material, although at the expense of requiring more complicated and expensive dies. In this modification, the lever 148 has an arm 149 that slopes down from the fulcrum 128 and carries a pivot 150 for the anti-friction wheel 151 at a point below and in towards the center 50 of the sweeper from the axle 152. The anti-friction wheel 151 is cup shaped and has an in-turned rim 153 which bears on the upper and outer side of the axle 152, the axle projecting into the hollow side of the anti-friction wheel. 55 The center of the anti-friction wheel 151 is bossed in so that the bearing 150 will lie in the plane 60 of the rim 153 upon which the load is carried.

65 The hub 154 of the floor wheel 155 is a trifle shorter than the hub 117 of the floor wheel 114 of the sweeper shown in Figures 12 to 14, and the axle 152 is a little shorter, but the construction is otherwise the same. The same type of spring may be used, and it hooks into a hole 156 in an outwardly projecting ear 157 on the end of the 70 arm 149 of the lever.

75 The sweepers described above incorporate not only a single invention but several inventions, and they may be carried out not only as shown but in many other ways, some of which may even involve further invention. The inventions de-

11

scribed here therefore include any construction or device falling within the terms of any one of the following definitions.

I claim:

1. A carpet sweeper having a case, a handle pivoted on the case, a rotary brush in the case, pivots on which the brush can rotate, friction pulleys on the ends of the brush, wheels that can roll on the floor or carpet and drive the brush roll on the floor or carpet and drive the brush through the friction pulleys, and high-low mechanisms for moving the brush pivots and the brush down with respect to the case when the wheels move up with respect to the case, there being only one connection between the high-low mechanism and each wheel, and each of these connections being constructed and arranged to press the wheel down and in towards the brush pulley at an angle of approximately forty-five degrees to the vertical so that the portion of the pressure transmitted by this connection and pressing the wheel against the brush pulley is great enough to prevent the floor wheel from slipping on the brush pulley.

2. A carpet sweeper as defined in claim 1 and in which the connections between the high-low mechanisms and the wheels include slots that are inclined down and out at angles of about forty-five degrees to the horizontal.

3. A carpet sweeper as defined in claim 1 and in which the connections between the high-low mechanisms and the wheels are rollers which are carried by the levers and which roll on the upper and outer sides of the axles of the wheels.

4. In a floor and carpet sweeper having wheels and a brush and a case and a handle pivot, and a mechanism connected to the wheels and the brush and the handle pivot for moving the brush down relative to the handle pivot when the handle pivot is moved down relative to the wheels, the only connection between that mechanism and each of the wheels being a means for guiding that wheel relative to the adjacent portion of the mechanism in an oblique path extending up and towards the axis of the brush at an angle of approximately forty-five degrees to the horizontal.

5. A mechanism as defined in claim 4 and in which the wheel has an axial projection and in which the connection to the wheel is a roller that bears on the axial projection.

6. In a floor and carpet sweeper having a case, a rotary brush with one or more friction pulleys thereon, one or more wheels adapted to roll on the floor and engage the friction pulleys and thereby drive the brush, and a handle pivot bearing fixed to the case, the combination of a mechanism connected to the wheels and to the brush and to the handle pivot bearing and constructed and arranged to move the brush down relative to the handle pivot bearing when the handle pivot bearing is moved down relative to the wheels, and a single connection between said mechanism and each of the wheels, each of said connections being obliquely movable and constructed and arranged to press its wheel against one of the brush pulleys as hard as it presses its wheel down.

7. A carpet sweeper of the character described comprising a casing, floor wheels for the casing, floating axles for the floor wheels, a brush, brush pivots on which the brush is supported for rotation and for vertical shifting movement, and spring means comprising a spring carried by and acting on oppositely extending vertically rigid levers located at each end of the casing and

12

having their inner end portions interconnected with and pressing downwardly on the brush through the brush pivot, their outer end portions interconnected with and pressing inwardly and downwardly on the floor wheels, and their central portions intermediate the points of interconnection with the brush and the floor wheels fulcrumed on a fulcrum support member mounted on the casing whereby said spring means functions to transmit upward and downward movement of the floor wheels to the brush while reversing the direction of such movement, portions of said spring means and said fulcrum support member being laterally springy enough and free to move out from the casing just enough to withdraw the brush pivot at least halfway but not all of the way out of the brush.

8. A carpet sweeper having a case, a handle pivoted on the case, a rotary brush in the case, pivots on which the brush can rotate, friction pulleys on the ends of the brush, wheels that can roll on the floor or carpet and drive the brush through the friction pulleys, and high-low mechanisms for moving the brush pivots and the brush down with respect to the case when the wheels move up with respect to the case, the only connection between the high-low mechanism and each wheel being a link extending up and away from the axis of the brush at an angle of approximately forty-five degrees to the horizontal.

9. In a carpet sweeper having a case and an axle, a connection from the case to the axle including a small wheel rolling on the upper outer side of the axle.

10. In a carpet sweeper having a case, a rotary brush in the case, friction pulleys on the ends of the brush, brush pivots projecting into the ends of the brush, wheels that can roll on the carpet and drive the brush through its friction pulleys, and end covers fixed to the ends of the case and enclosing the ends of the brush and the friction pulleys and the wheels, the improvement which consists of fulcrums on the end covers between the axes of the brush and the wheels, and springy brush-adjusting levers mounted on the fulcrums inside of the end covers and connected to the wheels and the brush pivots for moving the brush down when the wheels move up, each of the brush pivots being fixed to the inner end of one lever and having a pin-and-slot connection with the inner end of another lever, and there being just enough clearance between the inner ends of the levers and the end covers and the levers being springy enough so that their inner ends can be sprung out towards the end covers far enough to move each brush pivot out a distance equal to at least half but not all of the distance that it normally projects into the end of the brush, whereby either end of the brush can be freed from its pivot by simultaneously springing that pivot towards the adjacent end cover and springing the brush and the other brush pivot towards the other end cover, and the brush can then be removed by swinging its free end out of the case and moving the brush endwise away from the other brush pivot.

11. A carpet sweeper as defined in claim 10 and in which each lever has two independent arms extending one to a fulcrum and the other to the brush pivot, the two arms extending in the same general direction from where they join together so that one of the arms is longer than the distance from the fulcrum to the brush pivot.

12. A carpet sweeper as defined in claim 10 and

in which each of the levers has a slot which slopes down and out and through which it is connected to one of the wheels.

13. In a floor and carpet sweeper having wheels and a brush and a case, levers connected to the wheels and the brush and pivoted on the case for moving the brush down relative to the case when the case is moved down relative to the wheels, the only connection between the levers and one of the wheels being a means for guiding the wheel relative to the lever in an oblique path extending up and towards the axle of the brush at an angle of approximately forty-five degrees to the horizontal.

14. In a carpet sweeper having a brush pulley located between and driven by frictional contact with a pair of floor wheels, a pair of fulcrums on a fixed part of the sweeper, one fulcrum being located between the axes of the brush pulley and one of the wheels and the other fulcrum being located between the axes of the brush pulley and the other wheel, lever mechanism extending between and beyond the fulcrums and connected to the fulcrums, the lever mechanism being constructed and arranged to bend up and down in its central portion between the fulcrums, means connecting the central portion of the lever mechanism to the brush pulley for moving it up and down, and means connecting the outer portions of the lever mechanism to the wheels, the last mentioned means including axle members on which the wheels are mounted and surfaces on the outer portions of the lever mechanism extending down and out at angles of approximately forty-five degrees to the horizontal and slidably engaging the axle members so as to transmit forces between the lever mechanism and the wheels along lines sloping down and in below the brush pulley at a great enough angle to the vertical to intersect a short distance below the brush pulley and to force the wheels against the brush pulley hard enough to prevent slipping between them when the sweeper is in use.

15. A carpet sweeper of the character described comprising a casing, floor wheels for the casing, floating axles for the floor wheels, a brush supported for rotation and for vertical shifting movement, and spring means at each end of the casing and having portions interconnected with and pressing downwardly on the brush, portions interconnected with and pressing inwardly and downwardly on the floor wheels, and portions intermediate the points of interconnection with the brush and the floor wheels fulcrumed on the casing whereby said spring means functions to transmit upward and downward movement of the floor wheels to the brush while reversing the direction of such movement, the spring means comprising two levers and a spring carried by and interconnecting the levers, and the portions of the spring means interconnected with the floor wheels being parts of the levers lying above and outside the axes of the wheels and pressing downwards and inwards on the wheels.

16. A carpet sweeper of the character described comprising a casing, floor wheels for the casing, floating axle members for the floor wheels, a brush supported for rotation and for vertical shifting movement, and spring means at each end of the casing and having portions interconnected with and pressing downwardly on the brush, portions interconnected with and pressing inwardly and downwardly on the floor wheels, and portions intermediate the points of interconnection with the brush and the floor wheels fulcrumed on the

casing whereby said spring means functions to transmit upward and downward movement of the floor wheels to the brush while reversing the direction of such movement, the spring means comprising two levers and a spring carried by and interconnecting the levers, and the portions of the spring means interconnected with the floor wheels being parts of the levers bearing upon the upper and outer sides of the axle members and movable relative to the axle members along paths intersecting above the axis of the brush.

17. A carpet sweeper of the character described comprising a casing, floor wheels for the casing, floating axle members for the floor wheels, a brush supported for rotation and for vertical shifting movement, and spring means at each end of the casing and having portions interconnected with and pressing downwardly on the brush, portions interconnected with and pressing inwardly and downwardly on the floor wheels, and portions intermediate the points of interconnection with the brush and the floor wheels fulcrumed on the casing whereby said spring means functions to transmit upward and downward movement of the floor wheels to the brush while reversing the direction of such movement, the spring means comprising two levers and a spring carried by and interconnecting the levers, and the portions of the spring means interconnected with the floor wheels being parts of the levers engaging the axle members and preventing them from rotating freely.

18. A carpet sweeper of the character described comprising a casing, floor wheels for the casing, floating axle members for the floor wheels, a brush supported for rotation and for vertical shifting movement, and spring means at each end of the casing and having portions interconnected with and pressing downwardly on the brush, portions interconnected with and pressing inwardly and downwardly on the floor wheels, and portions intermediate the points of interconnection with the brush and the floor wheels fulcrumed on the casing whereby said spring means functions to transmit upward and downward movement of the floor wheels to the brush while reversing the direction of such movement, the spring means comprising two levers and a spring carried by and interconnecting the levers, and the portions of the spring means interconnected with the floor wheels being parts of the levers engaging the axle members and preventing them from rotating freely.

PAUL HEFTLER.
